UNITED STATES PATENT OFFICE.

ARTHUR TREVOR DAWSON, OF WESTMINSTER, LONDON, AND JAMES HORNE, OF BARROW-IN-FURNESS, ENGLAND, ASSIGNEES TO VICKERS LIMITED, OF WESTMINSTER, ENGLAND.

BREECH-ACTUATING APPARATUS OF HEAVY GUNS.

1,072,319.

Specification of Letters Patent.

Patented Sept. 2, 1913.

Application filed January 2, 1913. Serial No. 739,671.

To all whom it may concern:

Be it known that we, ARTHUR TREVOR DAWSON, knight, and JAMES HORNE, both subjects of the King of Great Britain, residing, respectively, at Vickers House, Breadway, Westminster, in the county of London, England, and Naval Construction Works, Barrow-in-Furness, in the county of Lancaster, England, have invented certain new and useful Improvements in or Relating to the Breech-Actuating Apparatus of Heavy Guns, of which the following is a specification.

This invention relates to breech actuating apparatus of the kind in which the breech actuating motor is situated on the slide frame and is provided with means whereby it operates to open the breech during the run out movement of the gun and to close the breech when the loading tray assumes its lowest position. According to this invention the means for controlling the breech actuating motor comprise two valve (one of which may form the seat for the other), so constructed and arranged that during the recoil movement of the gun they operate to maintain the motor stationary, and during the run out movement cause pressure fluid to be admitted to the motor to open the breech. The arrangement is also such that as the hinged loading tray is raised, movement is imparted to a spring device forming part of the valve mechanism so that during the downward movement of the tray the said device engages with one of the valves to shift it into a position to admit pressure fluid to the motor for closing the breech.

In order to bring the motor gently to rest as the breech block reaches its fully open and closed positions and also to suspend the opening of the breech if the run out of the gun is interrupted, we employ a reciprocating member such as a plate actuated by the motor, which plate is adapted to become engaged with and disengaged from one of the valves at the correct time and in the proper sequence.

In order that our said invention may be clearly understood and readily carried into effect, we will describe the same more fully with reference to the accompanying drawings, in which—

Figure 1 is a side elevation and Fig. 2

is a partial end elevation of a gun and mounting provided with our improvements. Fig. 3 is a side elevation of the mechanism that effects the movements of the valves. Fig. 3^a is a side elevation of a part of the valve mechanism hereinafter referred to, and Fig. 3^b is a side elevation of the aforesaid plate. Fig. 4 is a sectional end elevation of Fig. 3. Figs. 4^a, 4^b, 4^c and 4^d are sections taken through the ports of one of the valves and the casing, Figs. 4^a and 4^c being sections on the same line but viewed in opposite directions and with the valves in different positions. Fig. 5 is a side elevation of the valves in position in their casing. Fig. 6 is a side elevation of the mechanism at the rear of the said valves and Figs. 7 and 8 are side elevations of the valves removed from their casing. Figs. 9 to 15 show diagrammatically certain positions that the valves and the principal parts of their mechanism occupy during the recoil and run out of the gun, and the raising and lowering of the loading tray.

A is the gun and B the cradle that recoils therewith.

C is the slide frame for the cradle, C' is the loading tray and C² is the breech actuating motor.

D and E represent the aforesaid valves and F represents their casing.

G represents the aforesaid plate operated by the breech actuating motor.

In the example illustrated, the valves D and E are of the rotary kind having their working faces in contact, the valve D constituting the seat for the valve E and being provided with an exhaust port d and with two ports d', d² which respectively control the opening and the closing movements of the motor C². These ports terminate on the cylindrical portion of the valve D at different distances from the face of the valve as is shown in Fig. 4. The said ports communicate with independent annular channels formed by the packing rings of the valve D. The valve casing F has ports f, f' (Figs. 4 and 4^a) connected to pressure and exhaust pipes f^x, f'^x (Fig. 1) and has two other ports f², f³ (Figs. 4^b and 4^c and 5) connected to pipes f^{2x}, f^{3x} (Figs. 1 and 2) one or the other of which conveys pressure fluid to the motor for causing it to open and close the breech.

in accordance with whichever of the ports d' , d^2 is open to pressure fluid. The pressure fluid supply port f communicates as shown in Fig. 4^d with a cavity in the valve D in which the valve E is adapted to move. The spindle of the valve D is, in the example shown, provided with a pinion D' (Figs. 4 and 6) gearing with a rack D² attached to a connecting rod D^x which is pivoted to a bell-crank lever C^x (Fig. 1) on the slide frame. The free end of the said lever is adapted to engage with a cam groove B^x on the cradle, so that the aforesaid valve D is angularly displaced in opposite directions during the recoil and run out of the gun. The arrow in Figs. 5, 9 and 10 indicates the direction of movement of the valve D during recoil of the gun.

The valve E is formed with a depression e (Figs. 4 and 8) for the purpose of placing either of the ports d' , d^2 of the valve D in communication with the exhaust port d . The spindle of the valve E has a squared end e' that engages in a square recess (Fig. 4) 25 in the boss of a lever E' (Fig. 3^a) having a pin E^o that is pivoted in a bracket E^x connected to the slide frame. A spring e^2 (Fig. 4) is disposed in the said recess to retain the valve E on the face of the valve D. The lever E' carries a spring bolt E² under the control of a bell-crank lever e^{2xx} E^{2x} pivoted in the lever E', the arm E^{2x} engaging with the inner part of the spring bolt E². The said lever E' is adapted to receive a detachable handle E^x for moving the valve E when the breech motor is to be controlled by hand as will be hereinafter described. The spindle e' of the aforesaid hinged loading tray C' has an arm c'^x (Fig. 40 1) which is connected by a link C^x with an arm C³ pivoted co-axially with the rotary valves upon the boss of the lever E' and provided with a spring plunger c³ (constituting the aforesaid spring device) under the control of a bell-crank lever c^{3x} , C^{3x}, the arm C^{3x} engaging with the plunger c³.

The valve D is rocked during recoil of the gun, in the direction of the arrow in Figs. 5, 9 and 10, by the coöperation of the cam groove B^x with the bell crank lever C^x as aforesaid, and, a shoulder d'^x on the said valve coming into contact with a shoulder e'^x on the valve E as shown in Fig. 10, the valve D carries the valve E with it until the lower end of the aforesaid lever E' connected thereto bears against a stop g on the plate G which is loosely mounted on the pin E^o of the lever E' and has a series of teeth formed on its periphery with which engages a worm G^o operated by the motor C². The spring bolt E² carried by the said lever E' then engages in a recess g^x formed in a flange G^x on the plate G and the valve E is thereby locked to the plate as shown in Fig. 65 11. Meanwhile the "closing" port d^2 of

the valve D has been uncovered (Fig. 10) during the initial part of the movement of this valve and remains uncovered during the whole of the recoil movement so that the motor C² is retained in the position to keep the breech closed. During the run out movement of the gun the valve D is rocked in the direction of the arrow in Fig. 12 with the result that the "opening" port d' is uncovered as shown in Fig. 12 (the valve E being 70 locked to the plate G as aforesaid) and the breech motor C² is caused to commence to open the breech. During the opening of the breech the plate G is angularly displaced by the motor, carrying with it the 75 valve E, so that the valves are both moving independently in the same direction. When the gun has fully run out, the valve D reaches its normal position (Fig. 13) and, the breech continuing to open, the plate G 80 moves the valve E into the position indicated in Fig. 13. The "opening" port d' in the valve D is thus closed and the motor C² is gradually brought to rest with the breech block in the fully open position. If 85 the gun should not run out to the full extent, the valve D will not have reached its normal position under the influence of the cam groove B^x on the cradle, and the valve E will then overtake the valve D and close 90 its "opening" port d' , thereby bringing the motor to rest with the breech not fully opened.

In order to prevent damage to the gear in the event of the opening of the breech not 100 corresponding with the run out of the gun, such as occurs when the breech motor does not start as soon as the "opening" port is uncovered, the aforesaid spring bolt E² is formed with a beveled face E^{2xx} as shown in 105 Fig. 3, in such a manner that as the gun runs out, the valve D overtakes the valve E until shoulders d'^x , e'^x thereon coöperate, whereupon, the valve D moving faster than the valve E, the latter is positively moved 110 by the former and the bolt E² is forced clear of the recess g^x in the flange G^x of the plate G and the valves move together toward their normal position. After the valve D has reached this position, the plate G overtakes 115 the valve E and the stop g coöperates with the lever E' to move the valve E to its normal position so that the motor C² is brought to rest as aforesaid with the breech fully closed. The angle of the beveled face E^{2xx} 120 is such that under normal conditions the bolt E² will not be forced clear of the recess but will lock the lever E' of the valve E to the plate G as before described.

When the loading tray C' is raised by 125 the gun loading cage, the aforesaid arm C³ pivoted co-axially with the rotary valves is angularly displaced in the direction of the arrow in Fig. 3, and the spring plunger c³ carried thereby is moved out of contact with 130

the circular edge of the lever E' , so that the said plunger moves inwardly (as shown in Fig. 14) carrying therewith its controlling lever c^{3x} , C^{3x} . When the hinged loading tray is lowered, the aforesaid arm C^3 moves in the reverse direction to that mentioned above, and as the tray nears its lowest position the spring plunger c^3 engages with the arm e^{2xx} of the bell-crank lever e^{2xx} , E^{2x} (as shown in Fig. 15) to rock the latter in an anti-clockwise direction and move the spring bolt E^2 out of engagement with the recess g^x in the flange G^x of the plate G . By the further movement of the arm G^3 as the tray reaches its lowest position, the plunger c^3 , pressing against the edge of the lever E' and against the lever e^{2xx} —the latter being against a stop on the former—moves the lever E' connected to the valve E until the latter has uncovered the "closing" port d^2 in the valve D as shown in Fig. 15. The breech motor then commences to close the breech, during which operation the plate G is being angularly displaced in the direction of the arrow in Fig. 15. During this movement of the plate a cam surface G' engages with the arm C^{3x} of the controlling lever c^{3x} , C^{3x} of the spring plunger c^3 and moves the latter clear of the arm e^{2xx} of the bell-crank lever e^{2xx} , E^{2x} as shown in Fig. 9; a stop g' on the plate G then engages with the lever E' connected to the valve E and moves the latter into the position shown in Fig. 9 to cover the "closing" port d^2 , thus bringing the motor gently to rest with the breech fully closed. The parts are then in the normal position so that when the gun is again fired the above described cycle of operations is repeated.

When the valve E is to be actuated by the handle E'^x , the spring bolt E^2 and the spring plunger c^3 are retracted in any suitable manner against the resistance of their springs and retained in that position, the aforesaid connecting rod D^x being disconnected from its bell-crank lever C^x and attached to a fixed part of the mounting so that the valve D is locked in its normal position. The valve D thus forms a fixed seating for the manually operated valve E .

By the clause in the appended claims "of two valves in fluid connection with each other" is meant two valves one of which supplies fluid pressure to pass the other (when the latter is in the correct position) to the breech actuating motor.

What we claim and desire to secure by Letters Patent of the United States is:—

1. In breech actuating apparatus for ordnance, the combination with the pressure fluid breech actuating motor, of two rotary valves in fluid connection with each other, and means for causing relative angular movement to take place between the valves during the run out of the gun in order to

admit pressure fluid to the motor to open the breech.

2. In breech actuating apparatus for ordnance, the combination with the pressure fluid breech actuating motor, of two valves one forming the seat for the other, and means for causing relative movement to take place between the valves during the run out of the gun in order to admit pressure fluid to the motor to open the breech. 70

3. In breech actuating apparatus for ordnance, the combination with the pressure fluid breech actuating motor, of two valves in fluid connection with each other, and means for causing relative movement to take place between the valves during the recoil of the gun in order to admit pressure fluid to the motor to retain the breech closed and also for causing further relative movement to take place between the valves during the run out of the gun in order to admit pressure fluid to the motor to open the breech. 75 80

4. In breech actuating apparatus for ordnance, the combination with the pressure fluid breech actuating motor, of two valves one forming the seat for the other, and means for causing relative movement to take place between the valves during the recoil of the gun in order to admit pressure fluid 90 95 to the motor to retain the breech closed and also for causing further relative movement to take place between the valves during the run out of the gun in order to admit pressure fluid to the motor to open the breech. 100

5. In breech actuating apparatus for ordnance, the combination with the pressure fluid breech actuating motor, of two valves in fluid connection with each other, means 105 for causing relative movement to take place between the valves during the run out of the gun in order to admit pressure fluid to the motor to open the breech, and means for causing the motor to move one of the valves 110 so that their original relative position is restored and the supply of pressure fluid to the motor cut off.

6. In breech actuating apparatus for ordnance, the combination with the pressure fluid breech actuating motor, of two valves one forming the seat for the other, means for causing relative movement to take place between the valves during the run out of the gun in order to admit pressure fluid to the 115 120 motor to open the breech, and means for causing the motor to move one of the valves so that their original relative position is restored and the supply of pressure fluid to the motor cut off. 125

7. In breech actuating apparatus for ordnance, the combination with the slide frame and the pressure fluid breech actuating motor carried thereby, of two valves in fluid connection with each other, means 130

- for causing relative movement to take place between the valves during the run out of the gun in order to admit pressure fluid to the motor to open the breech.
- 5 8. In breech actuating apparatus for ordnance, the combination with the slide frame and the pressure fluid breech actuating motor carried thereby, of two valves one forming the seat for the other, and means 10 for causing relative movement to take place between the valves during the run out of the gun in order to admit pressure fluid to the motor to open the breech.
9. In breech actuating apparatus for ordnance, the combination with the slide frame and the pressure fluid breech actuating motor carried thereby, of two valves in fluid connection with each other, and means for causing relative movement to take place be- 15 tween the valves during the recoil of the gun in order to admit pressure fluid to the motor to retain the breech closed and also for causing further relative movement to take place between the valves during the 20 run out of the gun in order to admit pressure fluid to the motor to open the breech.
10. In breech actuating apparatus for ordnance, the combination with the slide frame and the pressure fluid breech actuating motor carried thereby, of two valves one forming the seat for the other, and means for causing relative movement to take place between the valves during the recoil of the gun in order to admit pres- 25 sure fluid to the motor to retain the breech closed and also for causing further relative movement to take place between the valves during the run out of the gun in order to admit pressure fluid to the motor 30 to open the breech.
11. In breech actuating apparatus for ordnance, the combination with the slide frame and the pressure fluid breech actuating motor carried thereby, of two valves in fluid connection with each other, means for causing relative movement to take place between the valves during the run out of the gun in order to admit pressure fluid to the motor to open the breech, and means for 35 causing the motor to move one of the valves so that their original relative position is restored and the supply of pressure fluid to the motor cut off.
12. In breech actuating apparatus for ordnance, the combination with the slide frame and the pressure fluid breech actuating motor carried thereby, of two valves one forming the seat for the other, and means for causing relative movement to take 40 place between the valves during the run out of the gun in order to admit pressure fluid to the motor to open the breech, and means for causing the motor to move one of the valves so that their original relative 45 position is restored and the supply of pressure fluid to the motor cut off.
13. In breech actuating apparatus, the combination with the slide frame and the pressure fluid breech actuating motor carried thereby, a valve seat formed with three ports, an exhaust pipe communicating with one of said ports, fluid pressure supply pipes communicating with two of said ports and the motor, means for oscillating said valve seat during the recoil and run out of the gun, a valve movable upon the face of the valve seat within certain limits, a member moved by the breech actuating motor, means for establishing a connection between said member and the valve at the end of the recoil movement of the gun, and means for breaking the said connection. 50
14. In breech actuating apparatus, the combination with the slide frame and the pressure fluid breech actuating motor carried thereby, a valve seat formed with three ports, an exhaust pipe communicating with one of said ports, fluid pressure supply pipes communicating with two of said ports and the motor, means for oscillating said valve seat during the recoil and run out of the gun, a valve movable upon the face of the valve seat within certain limits, a plate, means for rocking said plate by the opening and closing movements of the breech actuating motor, a spring controlled device for establishing a connection between the plate and the valve at the end of the recoil movement of the gun, and means for moving said spring controlled device out of engagement between the plate and valve. 55
15. In breech actuating apparatus for ordnance, the combination with the gun loading tray and the pressure fluid breech actuating motor, of two valves in fluid connection with each other, and means for causing relative movement to take place between the valves during the lowering of the tray in order to admit pressure fluid to the motor to close the breech. 60
16. In breech actuating apparatus for ordnance, the combination with the gun loading tray and the pressure fluid breech actuating motor, of two valves one forming the seat for the other, and means for causing relative movement to take place between the valves during the lowering of the tray in order to admit pressure fluid to the motor to close the breech. 65
17. In breech actuating apparatus for ordnance, the combination with the gun loading tray and the pressure fluid breech actuating motor, of two valves in fluid connection with each other, means for causing relative movement to take place between the valves during the lowering of the tray in order to admit pressure fluid to the motor to close the breech and means for causing the 70

motor to move one of the valves so that their original relative position is restored and the supply of pressure fluid to the motor cut off.

18. In breech actuating apparatus for 5 ordnance, the combination with the gun loading tray and the pressure fluid breech actuating motor, of two valves one forming the seat for the other, means for causing 10 relative movement to take place between the valves during the lowering of the tray in order to admit pressure fluid to the motor to close the breech, and means for causing 15 the motor to move one of the valves so that their original relative position is restored and the supply of pressure fluid to the motor 20 cut off.

19. In breech actuating apparatus for 25 ordnance, the combination with the slide frame, the gun loading tray and the pressure fluid breech actuating motor mounted on said slide frame, of two valves in fluid connection with each other and means for causing relative movement to take place between the valves during the lowering of the 30 tray in order to admit pressure fluid to the motor to close the breech.

20. In breech actuating apparatus for 35 ordnance, the combination with the slide frame, the gun loading tray and the pressure fluid breech actuating motor mounted on said slide frame, of two valves one forming the seat for the other and means for causing relative movement to take place between the valves during the lowering of the 40 tray in order to admit pressure fluid to the motor to close the breech.

21. In breech actuating apparatus for 45 ordnance, the combination with the slide frame, the gun loading tray and the pressure fluid breech actuating motor mounted on said slide frame, of two valves in fluid connection with each other, means for causing relative movement to take place between the valves during the lowering of the tray 50 in order to admit pressure fluid to the motor to close the breech, and means for causing the motor to move one of the valves so that their original relative position is restored and the supply of pressure fluid to the motor cut off.

22. In breech actuating apparatus for 55 ordnance, the combination with the slide frame, the gun loading tray and the pressure fluid breech actuating motor mounted on said slide frame, of two valves one forming the seat for the other, means for caus-

ing relative movement to take place between the valves during the lowering of the tray in order to admit pressure fluid to the motor to close the breech, and means for causing 60 the motor to move one of the valves so that their original relative position is restored and the supply of pressure fluid to the motor cut off.

23. In breech actuating apparatus for 65 ordnance, the combination with the slide frame, the gun loading tray and the pressure fluid breech actuating motor mounted on said slide frame, of two valves one forming the seat for the other, a member moved 70 by the tray in raising and lowering, means on said member for co-operating with a part moving with one of said valves, a plate moved by the motor, and means whereby the said plate engages with the last mentioned 75 valve.

24. In breech actuating apparatus for 80 ordnance, the combination with the slide frame, the hinged gun loading tray and the pressure fluid breech actuating motor carried by said slide frame, of a valve seat formed with three ports, an exhaust pipe communicating with one of said ports, fluid pressure supply pipes communicating with two of said ports and the motor, means for 85 oscillating said valve seat during the recoil and run out of the gun, a valve movable upon the face of the valve seat within certain limits, a member moved by the breech actuating motor, means for establishing a 90 connection between said member and the valve at the end of the recoil movement of the gun, an arm moved by said loading tray, a device carried by said arm for breaking the said connection and for moving the 95 valve to admit pressure fluid to the motor to close the breech, and a stop on the member operated by said motor for returning the valve to the cut off position.

In testimony whereof we affix our signatures in presence of two witnesses.
